(57) **ABSTRACT**

The lighting control apparatus has a memory unit, an operation input unit and a control unit. The memory unit stores an outer frame and addresses of luminaires and operating devices. The operation input unit inputs to designate a position where a small area is provided in a predetermined area on a layout drawing. The control unit provides, based on the outer frame and the addresses, a layout drawing that illustrates positions where luminaires and operating devices are arranged in the predetermined range within the outer frame. The control unit determines the luminaire and the operating device arranged in the small area. The control unit gives an operation right of the luminaire arranged in the small area to the operating device arranged in the same small area.

**LIGHTING CONTROL APPARATUS,
LIGHTING CONTROL SYSTEM AND
LIGHTING CONTROL METHOD**

**CROSS REFERENCE TO RELATED
APPLICATION**

This application claims priority to and the benefit of Japanese Patent Application No. 2011-191106 filed on Sep. 1, 2011, the entire contents of which are incorporated herein by reference.

TECHNICAL FIELD

The present invention relates to a lighting control apparatus and a lighting control system configured to assign an operation right of a plurality of luminaires arranged in a predetermined area to a plurality of operating devices and a lighting control method thereof.

BACKGROUND

Usually a plurality of luminaires are provided on each floor of a building. Furthermore, on each floor, a plurality of rooms can be formed by combining inner wall arrangements. The luminaires arranged in a plurality of formed rooms may preferably be operated by switches and the like provided on walls and posts in the rooms.

Conventionally, it is suggested that an address of each luminaire and an address of each operating device are registered, each position on which a partition is arranged is detected by a sensor, and a luminaire and an operating device that have an address corresponding to the room formed by the partition are combined (see Patent Documents 1 and 2).

It is also generally known that, instead of providing a sensor that detects arrangements of partitions, a building manager sets an input terminal for lighting control to combine luminaires and operating devices arranged in the same room.

CITATION LIST

Patent Literature 1: JP2009-191575A
Patent Literature 2: JP2010-251938A

SUMMARY

However, a building manager would need a special knowledge to set for combining luminaires and operating devices, and it has been desired that even a user who has no knowledge of managing a lighting control can easily set a combination of luminaires and operating devices.

The present invention has been conceived in light of the above circumstances and provides a lighting control apparatus, a lighting control system and a lighting control method to enable easy setting of combination of luminaires and operating devices according to the room assignment.

The lighting control apparatus according to the present invention includes:

a memory unit configured to store a layout drawing illustrating an arrangement of a plurality of luminaires and a plurality of operating devices in a predetermined area and addresses corresponding to respective positions where the luminaires and the operating devices are arranged;

an input unit configured to input to designate a position where a small area is provided in the predetermined area on the layout drawing; and

2

a control unit configured to determine, based on the addresses stored in the memory unit, the luminaires and the operating devices arranged in the small area designated by an input on the layout drawing, and to give an operation right of the determined luminaires to the operating devices arranged in the small area.

The control unit may preferably give a warning when at least one of the luminaire and the operating device is not arranged in the small area.

Furthermore, even if the luminaire is arranged and the operating device is not arranged in the small area, the control unit may not give a warning when a receiver corresponding to a wireless input device is arranged in the small area.

The plurality of operating devices may preferably include an operating unit provided on a wall constituting an outer periphery of the predetermined area or on a post.

Furthermore, the plurality of operating devices may preferably include an operation terminal associated with a predetermined position in a first area.

20 The control unit may preferably display and output the layout drawing and, to the layout drawing displayed and outputted, accept, from the input unit, the designation input of the position where the small area is arranged.

Furthermore, the control unit may preferably display and output the layout drawing and, to the layout drawing displayed and outputted, the input unit is a pointing device.

Moreover, the control unit may preferably accept an area designated by a drag operation from the pointing device as the designation input of the position where the small area is arranged.

30 A lighting control system according to the present invention includes:

a plurality of luminaires;

a plurality of operating devices;

35 a memory unit configured to store a layout drawing illustrating an arrangement of a plurality of luminaires and a plurality of operating devices in a predetermined area and addresses corresponding to respective positions where the luminaires and the operating devices are arranged;

40 an input unit configured to input to designate a position where a small area is provided in the predetermined area on the layout drawing; and

a control unit configured to determine, based on the addresses stored in the memory unit, the luminaires and the 45 operating devices arranged in the small area designated by an input on the layout drawing, and to give an operation right of the determined luminaires to the operating devices arranged in the small area.

A lighting control method according to the present invention includes steps of:

50 displaying and outputting a layout drawing illustrating an arrangement of a plurality of luminaires and a plurality of operating devices in a predetermined area;

55 inputting to designate a position where a small area is provided in the predetermined area on the layout drawing;

determining, based on addresses, stored in advance, corresponding to respective positions where the luminaires and the operating devices are arranged in the predetermined area, the luminaires and the operating devices arranged in the small area designated by an input on the layout drawing; and

60 giving an operation right of the determined luminaires to the operating devices arranged in the small area.

A lighting control apparatus according to the present invention configured as described above designates a position where a small area is arranged on a layout drawing, thus an operation right of luminaires in the small area is given to operation devices in the same small area, thereby enabling

assignment of an operation right of the luminaires to the operating devices in a simple manner.

BRIEF DESCRIPTION OF DRAWINGS

FIG. 1 is a block diagram illustrating a configuration of a lighting control system having a lighting control apparatus according to one embodiment of the present invention;

FIG. 2 is a layout drawing of luminaires and operating devices in a predetermined area;

FIG. 3 is a diagram illustrating a method of depicting a small area when a small area icon is clicked;

FIG. 4 is a diagram illustrating a method of depicting the small area when a wall icon is clicked;

FIG. 5 is a layout drawing illustrating a state where the small area is depicted in the predetermined area;

FIG. 6 is a diagram illustrating a small area recognized with respect to the small area depicted in FIG. 5; and

FIG. 7 is a diagram illustrating a state where a warning is displayed when a luminaire and an operating device are not arranged in the depicted small area.

DESCRIPTION OF EMBODIMENTS

The embodiment of the lighting control apparatus to which the present invention is applied will be described below with reference to the accompanying drawings.

FIG. 1 is a block diagram illustrating a configuration of a lighting control system having a lighting control apparatus according to one embodiment of the present invention. The lighting control system 100 is constituted by including a lighting control apparatus 101, a signal transmission line 102, a luminaire 103 and an operating device 104. The lighting control apparatus 101, a plurality of luminaires 103 and a plurality of operating devices 104 are connected via the signal transmission line 102.

The luminaire 103 has an illumination light source such as, for example, an LED light source, and can switch between light emission and extinction. In addition, the amount of illumination light can be adjusted. The operating device 104 is, for example, a switch for switching between light emission/extinction of the luminaire 103, a wall-mounted operation unit (fixed operation unit) having a dial for adjusting the amount of illumination light, or a wireless input terminal (operation terminal) having a changeover switch or a function for adjusting the amount of light and an operation means for adjustment. Operation input to any one of the luminaires 103 can be detected by the operating device 104.

As described below, the lighting control apparatus 101 enables setting of assignment of an operation right of each luminaire 103 to an operating devices 104. Assignment of an operation right of the luminaire 103 to the operating device 104 enables, based on an operation input thereto, switching between light emission/extinction or adjustment of the amount of light of the luminaire 103 of which the operation right is assigned.

Next, arrangement of luminaires 103 and operating devices 104 will be described. The lighting control system 100 is applied, for example, to the lighting of the whole building or of a specific floor of the building. A plurality of luminaires 103 and a plurality of operating devices 104 are respectively arranged on a specific position on a specific floor of the building. In the present embodiment, for example, luminaires 103 and operating devices 104 in any building are included in the lighting control system 100. A building manager may form small areas or passages in areas by using inner walls or partitions. In this case, the small area may not necessarily be

a sealed space, and may be a space having an opening portion and surrounded by a partition.

The wall-mounted operation unit is arranged on the inner face of outer wall of the building or on the surface of posts 5 inside the building. In addition, a receiver (access point and the like) configured to receive wireless signals (wireless LAN and the like) from the wireless input terminal is arranged on a predetermined position. For convenience of explanation, the position where a wireless input terminal is arranged refers to 10 a position where a receiver that has registered the position of the wireless input terminal is arranged.

Next, a configuration of the lighting control apparatus 101 will be described. The lighting control apparatus 101 is constituted by including a control unit 105, a monitor 106, a 15 memory unit 107 and an operation input unit 108 (pointing device such as a keyboard, a mouse and a touch panel).

The monitor 106 of the lighting control apparatus 101 displays a layout drawing 109 of luminaires 103 and operating devices 104 in a specific area, which is an area in which 20 the lighting control system 100 is used (see FIG. 2). In the layout drawing 109, the positions where the luminaires 103 and the operating devices 104 are arranged in the predetermined area are managed by coordinates on a two-dimensional plane and illustrated within an outer frame 110 also managed 25 by coordinates, which represents a boundary of the predetermined area. When the lighting control system 100 is applied to a plurality of floors of the building, each floor's layout drawing is displayed by a two-dimensional coordinate system. Moreover, in addition to the information on the two-dimensional coordinate, the information on the belonging floor is added to the information on the positions where each luminaire 103 and operating device 104 are arranged.

In order to display a layout drawing, in the memory unit 30 107, the outer frames 110 indicating a boundary of the predetermined area on floors of the building and addresses indicating a position (information on coordinates on two-dimensional plane and belonging floor) of each luminaire 103 and each operating device 104 within each outer frame 110 are stored in advance. The control unit 105 provides a layout 35 drawing based on the outer frames 110 and the addresses of the luminaires 103 and of the operating devices 104 within the outer frame stored in the memory unit 107 and displays the drawing on the monitor 106.

The lighting control apparatus 101 has a device assignment 40 mode. In the device assignment mode, based on an input to the operation input unit 108, the control unit 105 assigns an operation right of each luminaire 103 to an operating device 104. When the device assignment mode is selected, the control unit 105 can accept an operation input of depicting a small area on the layout drawing 109 and an operation input of executing an assignment.

For example, as illustrated in FIG. 3, when recognizing an operation input of clicking a small area icon 111 displayed on the monitor 106 in the device assignment mode, the control 45 unit 105 waits for a drag operation on the same two-dimensional coordinate system as that indicating positions of the luminaires 103 and the operating devices 104. That is, in the device assignment mode, the control unit 105 displays a layout drawing indicating positions of the luminaires 103 and the operating devices 104 on the monitor 106 and virtually expands a coordinate system that corresponds to the two-dimensional coordinate system for indicating their positions 50 on the monitor as well, thus transiting to a state ready to accept a range designation of the small area 112. When a drag operation for range designation is performed by a mouse and the like on the monitor, the control unit 105 recognizes a rectangle with a pair of vertices, a coordinate of the starting 55

point and a coordinate of the ending point of the drag operation, as a range designated as the small area **112**, and depicts the range on the layout drawing. Thus the control unit **105** recognizes the range of area designated by the two-dimensional coordinate system as the small area **112**. Even if the drag operation ends, the control unit **105** does not accept the end of drag operation when determining that a wall forming a small area **112** indicated by the ending coordinate is the luminaire **103**. Then when recognizing a click operation again on the position that does not overlap with the luminaire **103**, the control unit accepts the end of the drag operation.

Furthermore, as illustrated in FIG. 4, when recognizing an operation input of clicking a wall icon **113** displayed on the monitor **106**, the control unit **105** transits to a state ready to accept the operation input of depicting a wall by drag. The control unit **105** recognizes a line connecting between the coordinate at the starting point of the recognized drag operation and the coordinate at the end point thereof as a wall **114**, and depicts the wall **114** on the layout drawing. When the wall **114** overlaps with the luminaire **103**, the control unit **105** does not accept the start and the end of the drag operation as in the above-described case. The control unit **105** forms an area closed by a plurality of walls **114** and the outer frame **110**, thereby completing a depicting operation of small area **112**.

Moreover, the control unit **105** recognizes an area other than the depicted small area **112** as another small area **112**. For example, as illustrated in FIG. 5, when a range of small area **112** is designated in a part of the predetermined area, the control unit **105** recognizes the designated range as a first small area **112a** as illustrated in FIG. 6, and the remaining range as a second small area **112b** as well.

Each time a small area **112** is depicted, the control unit **105** determines whether or not at least one luminaire **103** and at least one operating device **104** are arranged in each of the recognized small areas **112**. When determining that either one of them is not present in the small areas **112**, the control unit **105** displays a warning thereof on the monitor **106** as illustrated in FIG. 7, for example. Further, the control unit **105** deletes the warning **115** by, for example, deleting the depicted small area **112** later. FIG. 7 illustrates an example where a luminaire **103** is included in the area designated as a small area **112**, but an operating device **104** is not included therein.

In the case where even a wireless input terminal (operation terminal) is also considered, the control unit **105** also determines, when determining whether or not a luminaire **103** and an operating device **104** are arranged in each small area **112**, whether a receiver and a wireless input terminal whose position is registered in the receiver are present even there is no operating device **104**. Furthermore, even if a small area does not have an operating device **104** the control unit **105** does not give a warning if there are a receiver and a wireless input terminal whose position is registered in the receiver in the small area. The control unit **105** gives a warning when there is neither an operating device **104** nor a receiver, or when there is a receiver but there is no wireless input terminal whose position is registered in the receiver in the small area **112**.

Next, when the control unit **105** recognizes an operation input of clicking the assignment icon **116** (see FIGS. 3 and 4) displayed, for example, on the monitor **106** after a small area **112** is depicted, it starts to assign an operation right of each luminaire **103** to operating devices **104**. When starting the assignment, the control unit **105** recognizes luminaires **103** and operating devices **104** arranged in the depicted small area **112**.

Note that when the above-described receiver is provided, the memory unit **107** stores the information on the position where the receiver is arranged (two-dimensional coordinate

and the belonging floor) in advance. Then the control unit **105** also displays a receiver on the layout drawing based on the information on the position where the receiver is arranged, and recognizes the receiver included in the coordinate range of each small area **112** designated on the layout drawing. Thus the control unit **105** stores the receiver as that corresponding to each small area in the memory unit **107**.

Thereafter the control unit **105** gives an operation right of luminaires **103** arranged in the small area **112** to the operating device(s) **104** recognized as arranged in the same small area **112**. Giving of an operation right is performed for each small area **112**. In this case, the control unit **105** associates each operating device **104** with an address of luminaire **103** from which an operation right is assigned thereto, and stores the corresponding relation therebetween in the memory unit **107**. When a plurality of operating devices **104** are arranged in a single small area **112**, the control unit **105** gives an operation right of all luminaires **103** in the small area to all operating devices **104** in the same small area **112**.

In this case, it is possible to allow the control unit **105**, even after automatic assignment of an operation right of all luminaires **103** to all operating devices **104** in the single small area **112**, to assign an operation right of a luminaire **103** on a predetermined position to each operating device **104** by input to an operation input unit **108** after the automatic assignment of an operation right.

According to the lighting control apparatus of the present embodiment configured in the above-described manner, a small area **112** depicted on the layout drawing **109** that visualizes arrangement of luminaires **103** and operating devices **104** controlled by a lighting control apparatus **101** in a predetermined area can be depicted on a monitor **106** so that it is visually recognized and, by designating a range to be a small area **112** on the monitor, an operation right of luminaires **103** in a designated range is automatically assigned to operating devices **104** in the same range. Thus even a user without expertise can easily and intuitively assign an operation right of luminaires **103**.

Thereafter when a user in any one of small areas performs an operation input to switch between light extinction and emission or to change the luminance using an operating device **104** arranged in the area, the control unit **105** refers to the memory unit **107**. Then the control unit **105** locates, based on the reference, the address of the luminaire **103** associated with the operated operating device **104**, and performs switching between light extinction and emission and changing of the luminance of the luminaire **103** having the located address. Thus, regardless of any partition into small areas, it is certain that each operating device **104** is given an operation right of a luminaire **103** that is in the same room as the operating devices **104**.

Further, according to the lighting control apparatus of the present embodiment, a warning is displayed when at least one luminaire **103** and at least one operating device **104** are not arranged in a depicted small area **112**, thus at least one luminaire **103** can be arranged in small areas **112** and an operating device **104** that can operate each arranged luminaire **103** can be arranged therein as well.

Although the present invention has been described based on drawings and the embodiment, it should be noted that a person skilled in the art can easily perform various variations or modifications based on the disclosure. Therefore it should be noted that such variations or modifications are included in the scope of the present invention.

For example, in the above-described embodiment, an ID may be given to each user in advance and a user who may operate in a device assignment mode can be managed by the

ID and can be stored in the memory unit 107. Further, ranges where an operation in a device assignment mode is allowed or floors on which an operation is allowed may vary with IDs. In this case, when the control unit 105 detects an input of a predetermined ID by a user, it allows the user to operate in a device assignment mode only in the range or on the floor corresponding to the ID, and displays the area to be operated on the monitor 106. With such a configuration, only a user who has a predetermined authority may assign an operation right of a luminaire 103 on a predetermined position to an operating device 104. For more concrete example, when one floor is partitioned into small sections and each section is lent to different stores, or when each floor is lent to different companies, assignment of luminaires can be changed, with a simple operation, by respective stores or companies only for the range lent to each store or company.

Although the example shows that the operation input unit 108 and the monitor 106 are provided one for each control unit 105 and memory unit 107, they may be provided more than one for each. Furthermore, the operation input unit 108 and the monitor 106 may be used as a display screen and an operation means of a wireless input terminal such as a smart phone. In this case, operation input is performed by connecting, via the Internet or the Intranet, to a server having a control unit 105 and a memory unit 107.

The invention claimed is:

1. A lighting control apparatus comprising:

a memory unit configured to store a layout drawing illustrating an arrangement of a plurality of luminaires and a plurality of operating devices in a predetermined area and addresses corresponding to respective positions where the luminaires and the operating devices are arranged;

an input unit configured to input to designate a position where a small area is provided in the predetermined area on the layout drawing; and

a control unit configured to determine, based on the addresses stored in the memory unit, the luminaires and the operating devices arranged in the small area designated by an input on the layout drawing, and to give an operation right of the determined luminaires to the operating devices arranged in the small area.

2. The lighting control apparatus according to claim 1, wherein the control unit gives a warning when at least one of the luminaire and the operating device is not arranged in the small area.

3. The lighting control apparatus according to claim 2, wherein, even if the luminaire is arranged and the operating device is not arranged in the small area, the control unit does not give a warning when a receiver corresponding to a wireless input device is arranged in the small area.

4. The lighting control apparatus according to claim 1, wherein the plurality of operating devices include an operating unit provided on a wall constituting an outer periphery of the predetermined area or on a post.

5. The lighting control apparatus according to claim 1, wherein the plurality of operating devices include an operation terminal associated with a predetermined position in an area.

6. The lighting control apparatus according to claim 1, wherein the control unit displays and outputs the layout drawing and, with respect to the layout drawing displayed and outputted, accepts by the input unit an input to designate the position where the small area is arranged.

7. The lighting control apparatus according to claim 1, wherein the control unit displays and outputs the layout drawing and, the input unit is a pointing device to the layout drawing displayed and outputted.

8. The lighting control apparatus according to claim 7, wherein the control unit accepts an area designated by a drag operation from the pointing device as an input to designate the position where the small area is arranged.

9. A lighting control system comprising:

a plurality of luminaires;

a plurality of operating devices;

a memory unit configured to store a layout drawing illustrating an arrangement of a plurality of luminaires and a plurality of operating devices in a predetermined area and addresses corresponding to respective positions where the luminaires and the operating devices are arranged;

an input unit configured to input to designate a position where a small area is provided in the predetermined area on the layout drawing; and

a control unit configured to determine, based on the addresses stored in the memory unit, the luminaires and the operating devices arranged in the small area designated by an input on the layout drawing, and to give an operation right of the determined luminaires to the operating devices arranged in the small area.

10. A lighting control method comprising steps of: displaying and outputting a layout drawing illustrating an arrangement of a plurality of luminaires and a plurality of operating devices in a predetermined area;

inputting to designate a position where a small area is provided in the predetermined area on the layout drawing;

determining, based on addresses, stored in advance, corresponding to respective positions where the luminaires and the operating devices are arranged in the predetermined area, the luminaires and the operating devices arranged in the small area designated by an input on the layout drawing; and

giving an operation right of the determined luminaires to the operating devices arranged in the small area.
